UNITED STATES PATENT OFFICE.

WILLIAM F. WILKE, OF LA FAYETTE, INDIANA.

PROPELLING MECHANISM.

1,218,027.

Specification of Letters Patent. Patented Mar. 6, 1917.

Application filed May 19, 1916. Serial No. 98,607.

To all whom it may concern:

Be it known that I, WILLIAM F. WILKE, a citizen of the United States, residing at La Fayette, in the county of Tippecanoe and State of Indiana, have invented new and useful Improvements in Propelling Mechanism, of which the following is a specification.

This invention relates to propelling mechanism for water, air and land craft the object in view being to provide a propeller, and actuating mechanism therefor, by means of which a strong sculling action is produced by the working surfaces of the propeller, the action being similar to that derived from a sculling oar when in the hands of an expert.

A further object of the invention is to so arrange the propeller and the actuating mechanism therefor that said mechanism may be driven by an engine carried by the craft.

With the above and other objects in view, the invention consists in the novel construction, combination and arrangement of parts, as herein described, illustrated and claimed.

In the accompanying drawings:—

Figure 1 is a plan view of a boat showing the propelling mechanism of this invention in its applied relation thereto.

Fig. 2 is a bottom plan view of the rear portion of the boat on an enlarged scale illustrating the operation of the propeller and a portion of its actuating mechanism.

Fig. 3 is a vertical longitudinal section taken in line with and through one of the propeller controlling and actuating levers.

In illustrating the present invention, I have shown the same as mounted upon a boat A but it will of course be understood as the description proceeds that the propeller and its actuating mechanism may be mounted upon and used in conjunction with land, water and air craft.

The propeller 1 is shown in the form of a thin blade which is preferably curvilinear in the direction of its length as shown in Figs. 1 and 2, said blade being connected by pivotal joints 2 to a pair of levers 3 and 4 by which the propeller blade is supported, carried and actuated. The propeller is preferably located in rear of the boat and the levers 3 and 4 are preferably located beneath the bottom 5 of the boat, the levers being connected by pivot joints 6 at their

rear extremities to a cross head or yoke 7 which is pivotally supported at 8 beneath the hull of the boat.

In connection with each lever 3 and 4, I employ a crank shaft 9, the crank 10 of which is shown as working through a bushing 11 in the lever, the lever and crank shaft being held in proper relation to each other by a nut, head or shoulder 12 on the bottom of the crank 10. The main body of the crank shaft extends through a stuffing box 13 in the bottom of the boat and has fast thereon within the boat, a spur gear 14. Between the spur gear 14, as illustrated in Fig. 1, there is arranged a master gear 15 which meshes directly with one of the gears 14 and indirectly with the other gear 14 by means of an interposed idler gear 16 which is used for the purpose of causing the crank shafts 9 to turn in opposite directions. Bearing a fixed relation to the gear 15 is a beveled gear 17 which meshes with and is actuated by another bevel gear 18 on an extension 19 of the shaft 20 of an engine conventionally shown at 21 and arranged within the body of the craft.

In view of the foregoing description, taken in connection with the accompanying drawings, it will now be understood that when the engine is in operation, the gear 15 is rotated and the crank shafts 9, by means of the gearing described, are simultaneously rotated in opposite directions, therefore imparting a corresponding move-

ment to the cranks 10. These cranks operate on the levers 3 to move both of said levers simultaneously in the same direction as indicated by full and dotted lines in Fig. 2. In said figure the dot and dash lines indicate the limit of movement of the propeller blade 1 in one direction and the dotted lines indicate the position of the propeller blade when it has reached a point about midway of its full stroke in one direction.

The full lines indicate the medial position of the propeller blade 1 when operating on the reverse stroke. It will be obvious upon an examination of Fig. 2 that the propeller blade 1 acts in a manner similar to the action of a sculling oar in the hands of an expert, said propeller blade having a shearing action causing it during a portion of its stroke to sweep the water rearwardly and slightly to one side and to have almost a direct rearward push on the

water as it approaches the limit of its movement in each direction. By reversing the direction of rotation of the engine, the action of the propeller is also reversed thereby driving the craft in a rearward direction.

It is to be understood that the propeller and its actuating mechanism are designed to be used with any character of craft to be propelled such, for example, as water, land and air craft. Furthermore, I reserve the right to make such changes in the form, proportion and minor details of construction as fall within the scope of the appended claims.

I claim:

1. The combination with a craft, of substantially parallel motion levers extending generally in a longitudinal direction with respect to the path of movement of the craft, a propelling blade pivotally connected to the outboard ends of said levers, a pivotal yoke connecting the inboard extremities of said levers, crank shafts journaled in the body of the craft and having their cranks operatively connected to said levers, and means

for equally and simultaneously rotating said cranks in opposite directions.

2. The combination with a craft, of substantially parallel motion levers extending generally in a longitudinal direction with respect to the path of movement of the craft, a propelling blade pivotally connected to the outboard ends of said levers, a pivotal yoke connecting the inboard extremities of said levers, crank shafts journaled in the body of the craft and having their cranks operatively connected to said levers, means for equally and simultaneously rotating said cranks in opposite directions, means for equally and simultaneously rotating said crank shafts in opposite directions, said operating means comprising gears on said crank shafts, other gears interposed between and meshing with the first named gears, said gears for causing the latter to simultaneously rotate in opposite directions; and actuating means for one of said interposed gears.

In testimony whereof I affix my signature.

WILLIAM F. WILKE.
